INSULATOR FOR AN ELECTRIC HEATING ELEMENT

Amos W. Hackman, Kirkland, Ill., assignor to
Emerson Electric Co., St. Louis, Mo.

Filed Oct. 5, 1970, Ser. No. 25,326

Term of patent 14 years

Int. Cl. D13—99

U.S. Cl. D26—10

FIG. 1.

FIG. 2.

FIG. 3.

FIG. 4.

FIG. 1 is a side elevational view of an insulator for an electric heating element, showing my design,

FIGS. 2 and 3 are end and perspective views, respectively, of the insulator, and

FIG. 4 is a sectional view corresponding to the line 4—4 of FIG. 2.

The insulator design is characterized by the three partially cylindric lobes extending the length of the insulator and wherein each lobe is formed with a truncated face extending inwardly from each end thereof.

I claim:

The ornamental design for an insulator for an electric heating element, substantially as shown.
